UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING APPARATUS.

Application filed April 17, 1916, Serial No. 91,565. Renewed November 22, 1920. Serial No. 425,888.

To all whom it may concern:

Be it known that I, EDMUND C. MORGAN, a citizen of the United States, residing in New York, in the county of New York and 5 State of New York, have invented certain new and useful Improvements in Mining Apparatus, of which the following is a specification.

This invention relates to apparatus for 10 mining coal and similar material, and has for its object the provision of apparatus of this character which shall be more economical and efficient in construction and operation. The invention is exemplified in the 15 combination and arrangement of parts shown in the accompanying drawings and described in the following specification, and it is more particularly pointed out in the appended claims.

20 In the drawings—Fig. 1 represents somewhat diagrammatically a horizontal section through a portion of a coal mine, showing the apparatus in operating position; Fig. 2 is a view similar to Fig. 1 but showing the 25 apparatus in position to begin operation; Fig. 3 is a top plan view of the mining machine forming a part of this invention; Fig. 4 is a side elevation of the machine shown in Fig. 3; Fig. 5 is a rear end elevation of 30 the machine shown in Fig. 3; Fig. 6 is a front end elevation of the machine shown in Fig. 3; Fig. 7 is a fragmentary sectional view on line 7—7 of Fig. 4; Fig. 8 is a fragmentary sectional view on the line 8—8 of 35 Fig. 7; Fig. 9 is a fragmentary sectional view on line 9—9 of Fig. 7; Fig. 10 is a top plan view of a conveyor forming part of the invention; Fig. 11 is an elevational view of the conveyor shown in Fig. 10 with some of 40 the parts in section; and Fig. 12 is a transverse sectional view of the conveyor shown in Figs. 10 and 11.

Referring more particularly to the drawings, the numeral 15 designates a vein of 45 coal to be mined; 16 and 17 are entries driven through the vein of coal spaced from one another and extending through the vein any distance which may be found desirable or convenient. A pillar of coal 15 left between the entries 16 and 17 is removed by 50 a series of cuts taken across the face of the

vein transversely to the direction of the entries 16 and 17. The machine for severing the coal from the pillar is made up of two sections, the front section 18 being designed 55 to sever the coal from the face of the vein while the rear section 19, deflects the coal from the position in which it is left by the section 18, breaks it into pieces and deposits it upon a conveyor 20 which extends along 60 the face of the vein being worked, and when it receives the coal from the machine transports it to one of the entries 16 where it is received by a second conveyor section 21, which in turn carries it to a car or other 65 transporting device by means of which it is still further transferred to the mine shaft.

The construction of the mining machine proper will best be understood by reference to Figs. 3 to 9 inclusive. The forward or 70 severing section 18 of the machine, is provided with a base 22 arranged to be drawn along the floor of a mine chamber. Extending upwardly from the base plate 22 is a guard wall or plate 23 which is curved, horizontally, and partially encloses the operating mechanism for the cutting apparatus. The forward edge of the plate 23, as shown in Figs. 3 and 7, is provided 75 with a thickened upright portion 24 having guideways 25 at one side thereof. A bar 26 is arranged to slide vertically in the guideways 25 and is held in place by a plate 27 secured to the member 24 by cap screws 28. The bar 26 has a pair 80 of lugs 29 and 30 secured thereto and projecting above and below the ends of the member 24 respectively. The lugs 29 and 30 are provided with screws 31 and 32 by means 85 of which the bar 26 may be adjusted vertically relative to the upright member 24. The upper and lower ends of the bar 26 are provided with curved guides 33 and 34 respectively, about which a cutter chain 35 is directed. Horizontal arms 36 and 37 extend 90 from the upper and lower ends of the bar 26 respectively and are provided at their forward edges with guideways for the chain 35. The bars 36 and 37 are curved at their outer ends and unite with a vertical cutter 95 bar 38 which connects the outer ends of the horizontal bars and forms a continuation of 100

the front edge of the inclined base plate 77 is a scoop or scraper 80 arranged to pick up any loose particles of material which may be lying on the floor of the mine in the path 5 of movement of the inclined section 77. The deflector or coal plow section 19 is connected with the cutter 18 by the cable 71 which is secured to the section 19 at 81, as shown in Fig. 3.

10 The backward and inward curvature of the portion 82 (Fig. 3) of the deflector plate 76, permits the top portion of the severed section 70 of the material being mined, to tip backwardly as the lower portion of 15 the section is moved outwardly by the deflector plate. In this way the detached portions of the core section of material are gradually tipped over on their sides as they are moved away from the face of the vein 20 onto the conveyor 20.

10 The construction of the conveyor will best be understood from Figs. 1, 2, 10, 11 and 12. As shown in Figs. 1 and 2, the section 20 of the conveyor is positioned along the face 25 of a mine vein and is spaced a sufficient distance from the vein to permit the cutter section 18 of the mining machine to move between the vein and the conveyor with the cutter frame extending into the face of the 30 vein to form a kerf for severing the material from the vein. The cutter section is guided along the conveyor frame on the guide flange 79 which cooperates with an overhanging flange 83 (Fig. 6) which is secured 35 to the outer edge of the base plate 22 of the cutter section 18 and corresponds to the flange 78 on the deflector or plow section 19. The conveyor proper is made up of a bed plate 85 (Fig. 12) on which the lower run 40 86 of an endless belt conveyor is arranged to travel. The upper run 87 of the conveyor is guided by flanges 88 projecting inwardly from the walls of the conveyor bed plate 85. The forward end of the conveyor is provided 45 with an upwardly inclined section 90 and a base plate 91 which extends beneath the upwardly inclined portion 90 is secured to the base plate 85 at the point where the section 90 begins its upward inclination.

50 Mounted on the base plate 85 adjacent the forward end of the inclined section 90, is the section 21 of the conveyor which receives the material from the section 20 and discharges it into a car or other transporting device. The section 21 is carried by a circular track 92 spaced upwardly from the base plate 91 and secured to the base plate by lag screws 93. The bed plate 94 of the conveyor section 21 has a plurality of downwardly projecting supporting posts 95 connected to its lower surface. The posts 95 are provided with notches 96 which cooperate with the track section 92 and support the conveyor section 21 in a manner to permit rotation of the section 21 in a horizontal

direction to provide for adjusting the position of the forward end of the section 21. This will permit the section 21 to discharge onto cars on either one of a pair of tracks that may be placed in the entry 16.

The conveyors are driven by a motor 97 mounted on the plate 91 and geared to drive a pair of shafts 98 and 99 journaled in pedestals 100 secured to the plate 91. The shaft 98 carries a drum 101 which may be clutched thereto by a clutch 102. The shaft 99 carries a pair of drums 103 and 104 which may be clutched to this shaft by clutches 105 and 106 respectively. The end of the shaft 98 opposite the drum 101 carries a bevelled pinion 107 which meshes with an idler gear 108 mounted to rotate on a pedestal 109 projecting upwardly from the plate 91. The idler 108 meshes with a pinion 110 secured to a shaft 111 rotatably mounted in bearings 112 carried on the under face of the bed plate 94. The shaft 111 carries a sprocket wheel 113 at its outer end which drives a chain 114 meshing with a sprocket wheel 115 on a shaft 116 arranged to drive the endless belt 117 of the conveyor section 21. Because of the idler gear 108, it is clear that the conveyor belt 117 may be driven through the mechanism described regardless of the angular position of the conveyor section 21 relative to the conveyor section 20.

The drum 101 has a cable 118 arranged to be wound thereon which is guided around pulleys 119 and 120 into the entry 16 where it is carried forwardly along the entry to any desired position and has its end fixedly secured in any suitable manner. The drum 103 carries a cable 121 which passes around pulleys 122 and 123 to a position in the entry 17 corresponding to the position of the cable 118 in the entry 16. It will be apparent that when the cables 118 and 121 are wound on their respective drums the conveyor will be drawn inwardly toward the face of the mine vein. The position of the conveyor is thus adjusted after each cut made by the mining machine. It will be seen that the direction pulleys 120 and 123 are each provided with a pair of oppositely disposed guide pulleys so that the cables 118 and 121 may be guided in either direction from the ends of the conveyor, thus making it possible to move the conveyor in either direction in the mine chamber.

The drum 104 is provided with a cable 125 which passes over a pair of guide pulleys 126 at the lefthand end of the conveyor section 20, as viewed in Figs. 1 and 10, and thence backwardly past the deflector section 19 to the cutter section 18 where the end of the cable is secured to the cutter section. When the cable 125 is wound on the drum 104 the cutter section 18 will be drawn backwardly until it engages the deflector section 19, after which both sections will be drawn

backwardly together until they reach a position adjacent the end of the conveyor section 20. After they have been brought to this position, the conveyor may be moved by the cables 118 and 121, to a new cutting position, the conveyor section 20 carrying with it the mining machine and also the discharge section 21 of the conveyor. It should be noted that during this movement of the conveyor into position for a new cut, the sections 18 and 19 of the mining machine are positioned close together, as shown in Fig. 2, thus bringing the parts of the machine into very small compass, to permit the machine to move into a very narrow entry before beginning its cut. If the parts of the machine were rigidly secured relative to one another, with the deflector plate 72 sufficiently removed from the cutter to permit the plate to 10 easily transfer the severed material after it has broken from its forward end by gravity, or to provide sufficient leverage for the plate itself to break comparatively hard material from the mine wall, a much wider entry 15 would be necessary to permit the machine to be moved into position to start a cut than is required by the present construction.

Since the severed material is deflected onto the conveyor by the forward movement of the machine, it is apparent that some of the material will be left in the position in which it is first placed when severed from the mine vein at the time when the machine has completed its movement across the face of the vein and finished the disconnection of a section. In order to care for this residual material, an abutment 130 is secured to the base member 91 of the conveyor and is rigidly held in position in alinement with the section of material being severed and at the end 30 of the path of movement of the loop core cutter. The abutment 130 is made of proper size to pass through the loop formed by the cutter chain and when the machine reaches the end of a cut its forward movement is continued a sufficient amount to force the material through the loop and onto the base plate 75 of the deflector section 19. If it is found necessary, the drum 61 may be rotated 40 to draw the deflector section 19 toward the cutter section 18 in order to bring all of the severed material onto the plate 75. When this has been done, the machine may be moved backwardly to its initial position and will carry with it the severed material that has not been discharged onto the conveyor 45 20. This material will be forced from the deflector section as soon as the next cut has been started.

60 By the mechanism described, material such as coal, found in approximately horizontal veins or layers, may be mined with a minimum degree of expense and danger. The entries 16 and 17 may be made very narrow so 65 that they will require no timbering. The

roof of the mine in the rear of the conveyor 20, is supported only a sufficient length of time to permit the operation of mining, and the timbering is removed from the mine as the conveyor section 20 moves forwardly, the 70 roof of the mine being allowed to fall in the rear of the operation. In this way all of the coal is removed and no timbering is left in the mine, and the operation is carried on rapidly and at a minimum expense. 75

I claim:

1. In a system of mining, the combination with a loop chain core-cutter having an unobstructed core-opening therethrough, of means for operating said core-cutter including feed thereof in a general horizontal direction, and means following said core-cutter and adjustably spaced therefrom to act on said core to displace the same laterally. 80

2. In a system of mining, the combination with core-cutting mechanism, of means for operating the same including feed thereof in a general horizontal direction to make a continuous cut along the face of the mine vein to cut a core, means following said core-cutting mechanism in position to act on the cut material and displace portions thereof successively from the mine wall, and means for adjusting the relative positions of said core-cutting mechanism and said displacing means. 90

3. In a mining system, the combination with means for cutting a single core of material along a mine wall in a general horizontal direction, of means for operating said core-cutting means, means for displacing the projecting core to break sections therefrom transversely, and means for adjusting the relative positions of said core-cutting means and said displacing-means. 100

4. In a mining machine, a device for severing a continuous core section from the face of a mine vein, means for moving said device along the face of said vein, a deflector for receiving said core connected with said severing device to be drawn therewith along said face, and means for adjusting said severing device and said deflector relative to one another. 110

5. In a mining machine, a device for severing a section of material from the face of a mine vein, comprising a cutter arranged to form a kerf extending inwardly from the upper face of said vein and encircling the section of material being severed on the sides thereof not previously disconnected by emerging from the lower face of such vein, and a deflector connected with said severing device and adjustable relative thereto for engaging the severed portion of said section and moving it laterally from its native position. 115

6. In a mining machine, a frame, a cutter carried at one side of said frame, a chute deflector connected with said frame in posi- 120 125

tion to contact with material severed by said cutter, and means for adjusting said frame and deflector relative to one another.

7. In combination, a mining machine frame, a cutter secured to said frame and forming an unobstructed core loop at one side thereof, a deflector connected with said frame in position to contact with material severed by said cutter, and means for adjusting said frame and deflector relative to one another.

8. In a mining machine, a frame, means for moving said frame along the face of a mine vein, a cutter forming an unobstructed core loop at one side of said frame and arranged to sever a section of material from a mine vein as said frame is moved along the face thereof, a deflector connected with said frame and extending into position at the rear of said cutter to contact with material severed by said cutter, and means for adjusting said cutter and deflector relative to one another.

9. In a mining machine, a frame, means for moving said frame along the face of a mine vein, a cutter carried by said frame at one side thereof and forming an unobstructed core loop for severing a core section from a mine vein as said frame is moved along the face thereof, a deflector secured to said frame in the rear of said cutter and spaced therefrom, and means for adjusting the distance between said cutter and said deflector.

10. In a mining machine, the combination with a supporting frame, of a loop chain core-cutter having an unobstructed core-opening therethru and mounted on the forward end of said frame with its cutting plane at right angles to the path of travel of said frame, means for actuating said core-cutter, and means for moving said frame rectilinearly transversely of said cutting plane to secure feeding movement of said core-cutter during the actuation thereof.

11. In a mining machine, the combination with a supporting frame, of core-cutting mechanism mounted thereon, means comprising a cable connected between said frame and said deflector for pulling the latter along behind said frame in position to engage the core and move the same laterally and means for operating said core-cutting mechanism including feed thereof by movement of said frame.

12. In a mining machine, the combination with a supporting frame, of core-cutting mechanism mounted thereon, a deflector separate from said frame, means comprising a cable for connecting said deflector to said frame, means for driving said core-cutting mechanism, and means for moving said frame to feed said cutting mechanism.

13. In a mining machine, the combination with a supporting frame, of core-cutting mechanism mounted thereon, a separate de-

flector frame, mechanism for confining said frames along the same path of travel, a haulage connection between said frames, means for driving said cutting mechanism, and means for moving both of said frames along said path.

14. In a mining machine, the combination with a supporting frame, of a loop chain core cutter mounted on said frame at the forward end thereof to extend from one side thereof and having an unobstructed core-opening therethru, a separate deflector frame, a guide for confining the movements of said frames in alinement with each other, a haulage connection between said frames for adjustably spacing said frames, means for driving said cutter, and means for moving said frames along said guide to secure feed of said cutter and to cause said deflector frame to engage the core and break it and move the dislodged pieces laterally away from the mine wall.

15. In a mining machine, the combination with a supporting frame, of a cutter bar rigidly secured to said frame in an upright position in fixed relation to said frame and having an unobstructed core-opening therethru, a flexible chain cutter mounted on said cutter to travel around said unobstructed core-opening in a cutting plane fixed relatively to said frame and extending at right angles of the forward portion thereof, and means for effecting rectilinear movement of said frame to secure feeding movement of said chain cutter during the actuation thereof.

16. In a mining machine, the combination with a supporting frame, of a cutter frame rigidly connected to the forward end of said supporting frame and extending therefrom laterally at right angles to the path of travel thereof, said cutter frame having an unobstructed core-opening extending therethru parallel to the path of travel of said supporting frame, a flexible chain cutter mounted on said cutter frame to travel around said unobstructed core-opening, means mounted on said supporting frame for driving said cutter chain, and means for moving said supporting frame rectilinearly to secure feeding movement of said cutter at right angles to the cutting plane at the forward end of said frame.

17. In a mining machine, the combination with a supporting frame, of a cutter frame rigidly secured to the forward end of said frame to move bodily with said supporting frame, said cutter frame having an unobstructed core-opening therethru for the passage of a core of material parallel to the path of travel of said supporting frame closely adjacent an upright mine wall, a flexible chain cutter mounted on said cutter frame to travel around said unobstructed core-opening, means mounted on said sup-

porting frame for driving said chain cutter, and means for moving said supporting frame along a mine wall to effect feeding movement of said cutter and cause the latter to complete the cutting of the core at substantially the limit of movement of said supporting frame.

18. In a mining machine, a frame, a cutter carried by said frame in position to form 10 a loop at one side thereof and having a chain cutter carried thereby at the forward edge of said frame, and a deflector secured to said frame in the rear of said cutter.

19. In a mining machine, the combination 15 with a supporting frame, of a flexible chain cutter, a cutter frame having an unobstructed core-opening therethru and mounted on said frame in fixed position relative thereto with its cutting plane permanently positioned 20 transversely of the direction of movement of said frame, and means for operating said cutter including rectilinear movement of said frame to secure feeding movement of said cutter.

20. In a mining machine the combination 25 with a supporting frame, of a cutter carried by said frame in position to form a loop having an unobstructed core-opening therethru and having its cutting plane extending 30 transversely of said frame and in advance of the forward end thereof, and means for operating said cutter including rectilinear feed of said frame to secure feeding movement of said cutter transversely of its plane.

35. 21. In a mining machine, the combination 40 with a supporting frame, of a rectangular cutter frame extending laterally from said supporting frame and permanently connected thereto in such fixed relation, said cutter frame having an unobstructed core-opening 45 therethru for the passage of a core of material parallel to the path of travel of said supporting frame, a chain cutter mounted on said cutter frame to cut a core having upper and lower plane surfaces and front and back vertical plane surfaces, means for 50 driving said cutter, and means for moving said supporting frame rectilinearly to secure feeding movement of said cutter.

55. 22. In a mining machine, a frame, means 55 for moving said frame along the face of a mine vein, a cutter bar carried by said frame permanently at the forward end thereof and arranged to form a loop at one side of said frame, and a cutter chain carried by said cutter bar and guided thereon in a plane permanently arranged transversely to the direction of movement of said frame and positioned at the forward 60 end of said frame.

65. 23. In a mining machine, the combination 65 with a supporting frame, of a cutter-frame extending laterally from said supporting frame at right angles to the path of movement of said supporting frame, said cutter

frame having an unobstructed core-opening therethru for the passage of a core of material parallel to the path of travel of said supporting frame, an upright guide plate at the inner side of said supporting frame 70 to engage the face of the mine wall during the movement of said supporting frame, a flexible chain cutter mounted on said cutter frame, means mounted on said supporting frame for driving said chain cutter, 75 and means for moving said supporting frame rectilinearly along the mine wall to secure feeding movement of said cutter while said upright guide plate slides along the face of the mine wall.

80. 24. In a mining machine, the combination with a supporting frame, of a cutter-frame mounted on said supporting frame to move bodily therewith and having an unobstructed core-opening therethru, an endless chain cutter mounted on said cutter-frame, means mounted on said supporting frame for driving said chain cutter, means for rectilinearly adjusting the elevation of said cutter frame 85 relatively to said supporting frame while 90 maintaining driving connection between said driving means and said chain cutter, and means for moving said supporting frame rectilinearly to secure feeding movement of said cutter.

95. 25. In a mining machine, the combination with a supporting frame, of a cutter frame having an unobstructed core-opening therethrough and mounted at the forward end of said supporting frame, means for driving said cutter chain to cut in a plane extending transversely of the direction of feeding movement of said cutter chain, means for moving said frames and said cutter chain bodily along the face of a mine vein to effect feeding movement of said cutter chain, and a guard connected to said supporting frame in position to protect that portion of the chain back of where said chain enters the mine wall and emerges 100 therefrom.

105. 26. In combination, a mining machine frame, means for moving said frame along the face of a mine vein, a cutter bar carried by said frame in position to form a loop at one side of said frame, an endless chain cutter mounted on said bar and guided thereby in a plane arranged transversely to the direction of movement of said frame, and a deflector connected with said frame 110 in the rear of the loop formed by said cutter bar.

115. 27. In combination, a mining machine frame, means for moving said frame along the face of a mine vein, a cutter bar carried by said frame at the forward end thereof and arranged to form a loop at one side of said frame, an endless chain cutter carried on said bar and guided thereby in a plane arranged transversely to the direc- 120 125 130

tion of movement of said frame, a motor carried by said frame for driving said cutter chain, and a deflector secured to said frame in the rear of said frame and cutter 5 and adjustable relative to said frame in the direction of movement thereof.

28. In mining apparatus, a frame, a kerf cutter carried thereby, a plow deflector for material severed by said cutter and 10 movable relative to said cutter, and a guide for controlling the movement of said deflector relative to said cutter.

29. In mining apparatus, a frame, a kerf cutter carried thereby, a plow deflector connected with said frame and movable relative thereto, and a guide for controlling the movement of said frame and deflector.

30. In mining apparatus, the combination with a supporting frame, of kerf-cutting mechanism carried thereby, means for driving said kerf-cutting mechanism, means for moving said frame along the face of the mine vein to effect feeding movement of said kerf-cutting mechanism, a chute deflector 20 spaced back of said supporting frame and comprising a unit separate from said supporting frame and kerf-cutting mechanism, and means for guiding said supporting frame and kerf-cutting mechanism and also 25 for guiding said chute deflector along substantially the same path of travel along the face of the mine vein.

31. In combination, a mining machine frame, a cutter carried by said frame, a 35 chute deflector adjustably connected with said frame in the rear of said cutter, and a guide for controlling the movement of said frame and deflector to retain said deflector in proper position relative to said cutter.

32. In mining apparatus, a frame, a loop core cutter carried by said frame at one side thereof, a deflector connected with said frame in the rear of said frame and cutter, means for adjusting said deflector 45 relative to said frame and cutter, and a guide for retaining said frame and deflector in proper alignment with one another during the movement of said frame and deflector.

33. In mining apparatus, the combination with a conveyer, of a severing unit adapted to travel along the face of the mine vein adjacent said conveyer, a separate deflector unit adapted to follow said severing unit along the path of travel of the latter, and means carried by said conveyer for retaining 55 said severing unit and said deflector unit in operative relation with said conveyer and for movement along the face of the mine vein over the same path of travel.

34. In mining apparatus, the combination with a conveyer comprising a supporting frame, of dislodging mechanism adapted to 60 move along said conveyer for dislodging

material from the face of a mine vein spaced a short distance from said conveyer, a deflector adapted to travel along said conveyer at adjustable distances back of said dislodging mechanism to direct the dislodged material onto said conveyer, and means on said supporting frame for holding the dislodging mechanism and the deflector in operative adjusted positions relative to one another and to said conveyer during the 75 operation of said dislodging mechanism.

35. In mining apparatus, a device for severing material from a mine vein, means for moving said device along the face of said vein, a conveyor for transferring material 80 severed by said device, a deflector connected with said device for directing material severed thereby onto said conveyor, means for adjusting said deflector toward and from said severing device in the direction of 85 movement of said device, and a guideway carried by said conveyor and co-operating with said severing device and said deflector for retaining the parts of said apparatus in operative relation to one another during the 90 movement of said severing device and said deflector.

36. In combination, a mining machine frame, an upright loop cutter carried by said frame at one side thereof, a conveyor for receiving material severed by said cutter, a deflector connected with said frame in the rear of said cutter and arranged to direct material severed by said cutter past the rear of said frame onto said conveyor, and means 100 carried by said conveyor for retaining said deflector in operative position.

37. In mining apparatus, a mining machine frame, a cutter carried at one side of said frame for severing material from a 105 mine vein, and a deflector adjustably connected with said frame and having a portion thereof positioned in the rear of said cutter and another portion extending around the rear of said frame.

38. In mining apparatus, the combination with a dislodging unit adapted to travel along the face of a mine vein and dislodge material therefrom, of a deflector unit adapted to travel along such face of the mine vein in the wake of said dislodging unit, a conveyer having a frame adapted to rest in stationary position on the floor of the mine chamber, means carried by said conveyer frame for confining the dislodging unit and the deflector unit to a predetermined path of travel, the deflector unit following the dislodging unit, means for operating the dislodging unit, and means for moving the deflector unit along said conveyer frame back 120 of said dislodging unit in position to direct the dislodged material onto said conveyer.

39. In mining apparatus, the combination with a conveyer adapted to be located along the face of the mine vein in a position spaced 130

therefrom, of dislodging mechanism connected to said conveyer to travel along the same to dislodge material from the face of the mine vein, separate mechanism adapted 5 to travel along said conveyer in the wake of said dislodging mechanism and in position to direct the dislodged material onto said conveyer, and means for permitting said dislodging mechanism to be brought into close 10 relation to said separate mechanism in a narrow entry at one side of the portion of the mine vein from which material is to be dislodged and directed to said conveyer.

40. In mining apparatus, the combination 15 with an elongated conveyer having a frame adapted to rest on the floor of a mine chamber in a position spaced from the face of a mine vein, of dislodging mechanism guided along said conveyer frame in position to dislodge material from the face of the mine vein parallel to said conveyer, a deflector guided along said conveyer in the wake of 20 said dislodging mechanism and at an adjustable distance back of said dislodging mechanism, means for connecting said dislodging mechanism to said deflector to cause said deflector to move with said dislodging mechanism when the latter is fed along the face of the mine vein while said deflector directs 25 the dislodged material onto said conveyer, and means for bringing said dislodging mechanism and said deflector into compact relation to reduce the combined length of 30 said deflector and dislodging mechanism longitudinally of said conveyer when said dislodging mechanism is in position to begin a cut along the face of the mine vein.

41. In mining apparatus, a conveyor having 35 one section arranged to be positioned along the face of a mine vein and another section arranged at an angle to said first section and arranged to be positioned in an entry at one side of the portion of said vein being worked, a device for severing material 40 from the face of said vein, a deflector connected with said device for directing material onto the first mentioned section of conveyor, and means for adjusting said severing device and deflector relative to one another 45 to permit said severing device to be positioned in an entry on the side of the portion of said vein being worked opposite that in which the second section of said conveyor is positioned.

42. In a system of mining, the combination 50 with a supporting frame, of a core-cutter having an unobstructed core-opening therethru and mounted on the forward end of said frame with its cutting plane extending transversely of said frame and in position 55 to permit the core of material to project longitudinally of said frame, means in position to follow said core-cutter to engage the projecting core to break the same, and means 60 for adjusting the space between the core-

cutter and breaking means and maintaining approximately the adjusted space during the 65 operation of said core-cutter, means for operating said core-cutter including rectilinear feed of said frame and cutter, and means for advancing the breaking means at the 70 adjusted distance back of the core-cutter.

43. In a mining machine, the combination 75 with a core cutter having an unobstructed core-opening therethrough, of means for operating the same, and means adjustably spaced from said core cutter for displacing 80 said core laterally.

44. In a mining machine, the combination 85 with a supporting frame, of an upright deflector mounted on said frame and curved relative to an upright axis in position to deflect mined material on said frame, and an extension flaring from the upper portion 90 of the curved deflector with the curvature of the flaring portion related to an axis extending in a general horizontal direction.

45. In a mining machine, the combination 95 with a supporting frame, of upright means on said frame for engaging material 100 and deflecting it transversely of said frame, and an upper lateral extension connected to the said upright deflecting means and curved therefrom toward the horizontal on an axis extending in a general horizontal direction.

46. A mining machine, the combination 105 with a frame having a platform movable along the floor of a mine and having a core receiving end, of an upright curved deflector extending from said receiving end to a discharge end of said frame, an upwardly inclined extension from said platform to said discharge end of said frame, and an upwardly curved lateral extension from said deflector to facilitate longitudinal twisting 110 of sections of said core while being moved toward said discharge end of said frame.

47. In a mining machine, the combination 115 with a core cutter, of a deflector for receiving the core from said core cutter, and means comprising a rope drum and a rope connected between said deflector and said core cutter for adjusting the distance between 120 said core cutter and said deflector.

48. In a mining machine, the combination 125 with a core cutter, of means for operating the same, a device for receiving and breaking the core, a frame for guiding said core cutter and said breaking device along the mine wall in alignment with each other, and means comprising a flexible connection between said core cutter and said deflector for adjusting the distance of said breaking device from said core cutter.

49. In a mining machine, the combination 130 with a frame, of core cutting mechanism mounted thereon, an upright curved plate on said frame, and mechanism back of said curved plate for operating said core cutting mechanism.

50. In a mining machine, the combination with core cutting mechanism, of means for driving the same, a frame, and an upright curved plate supported on said frame for carrying said driving means. 51. In a mining machine, the combination with a supporting frame, of a chain core cutter extending in a plane laterally from one corner of said frame, means for operating said core cutter to cut a single core, and a curved plate on said frame for supporting said actuating means and for protecting the latter from injury by the core cut by said core cutter. 10 52. In a mining machine, the combination with a supporting frame, of chain core cutting mechanism mounted thereon, apparatus for operating said core cutting mechanism to cut a single core, and a core guard plate also supporting said actuating apparatus. 20 53. In a mining machine, the combination with a supporting frame, of a cutter frame having an unobstructed core-opening therethrough, a chain cutter adapted to travel along said cutter frame, means on said supporting frame for driving said chain cutter, means for guiding said cutter frame along a rectilinear path of travel relatively to said supporting frame, and means for shifting the position of said cutter frame relative to said supporting frame while said cutter frame is guided along such rectilinear path of movement to adjust the position of the chain cutter as a whole relative to said 30 supporting frame. 35 54. In a mining machine, the combination with a supporting frame, of a chain cutter frame rigidly connected to said supporting frame and having an unobstructed core-opening therethrough and adjustably mounted on said supporting frame, means for shifting the position of said chain cutter frame as a whole on said supporting frame, a chain cutter guided on said chain cutter frame, and means on said supporting frame connected to said chain cutter for actuating the latter. 40 45 55. In a mining machine, the combination with a supporting frame, of a rectangular upright chain cutter frame adjustably mounted on said supporting frame, means for adjusting the position of said chain cutter frame as a whole on said supporting frame, and holding it in such adjusted position, a chain cutter guided on said chain cutter frame, the latter having an unobstructed core-opening therethrough, and means on said supporting frame comprising a sprocket wheel meshing with said chain cutter for actuating the latter in its various adjusted positions. 50 55 60 65 56. In a mining machine, the combination with a core cutter, of a supporting frame, means mounted on said supporting frame for actuating said core cutter, a deflector for receiving a core of material from said core cutter, and means comprising a rope drum on said supporting frame and a rope thereon connected to said deflector for adjusting the relative positions of said core cutter and said deflector. 70 57. In a mining and loading machine, the combination with a core cutter, of means for operating the same including the feeding thereof, a guide frame for said core cutter, an endless conveyor mounted on said guide frame, a deflector connected with said guide frame and following said core cutter, means for adjusting the relative space between said core cutter and said deflector, means for retracting said core cutter toward initial position, a pivoted conveyor extension, means for operating both of said conveyors, and means for shifting all of the aforesaid parts to a new starting position. 75 80 85 58. In a mining system, the combination with means for cutting a single core of material along a mine wall in a general horizontal direction, means for operating said core-cutting means, means for displacing the projecting core to break sections therefrom transversely, and rope gearing between said cutting means and said displacing means for adjusting the relative positions of said core-cutting means and said displacing means. 90 95 59. In a mining machine, the combination with mechanism for severing a continuous core section from the upright face of a mine vein, of a separate deflector adapted to occupy a position for receiving the core, and means comprising a flexible connection between said severing mechanism and said deflector for drawing said deflector along the path of said severing mechanism. 100 105 60. In a mining machine, the combination with a supporting frame, of core-cutting mechanism carried at the forward end thereof, a chute deflector constituting a unit separate from said supporting frame and the core-cutting mechanism thereon, and means comprising a flexible connection between said supporting frame and chute deflector unit for adjusting the distance between said supporting frame and said chute unit and drawing the latter along the path of said supporting frame in position to engage the material severed by said core-cutting mechanism. 110 115 61. In a mining machine, the combination with a supporting frame and core-cutting mechanism thereon to form one unit, of a deflector forming another unit separate from said first-named unit, and means comprising a rope connected between said units for adjusting the relative distance between them. 120 62. In a mining machine, the combination with a supporting frame, of a core-cutter projecting laterally from said frame and 125 130

having an unobstructed core-opening therethrough for the passage of a core extending along one side of said frame and parallel to the path of travel thereof, a separate 5 deflector unit adapted to occupy positions for engaging the rear end of said core, and means comprising a rope connected between said supporting frame and said deflector unit for adjusting the distance between said 10 supporting frame and said deflector unit and for pulling the deflector unit along behind said supporting frame.

63. In a mining machine, the combination 15 with a supporting frame, of an up-right standard carried by said frame, loop chain core-cutting mechanism having an unobstructed core-opening therethrough and mounted on said standard for vertical rectilinear adjustment thereon, and means for 20 preventing movement of said core-cutter in an arc about said standard.

64. In a mining and loading machine, the combination with a main frame, a conveyer 25 movable along said main frame, a supplemental frame mounted for longitudinal movement along said main frame, core-cutting mechanism mounted on said supplemental frame in rigid relation thereto and extending laterally from said main frame, 30 means for adjusting said core-cutting mechanism relative to said supplemental frame while being held in rigid relation therewith for bodily movement therewith, means for operating said core-cutting mechanism including rectilinear movement of said supplemental frame along said main frame, and means for directing the cut material 35 from said core-cutting mechanism onto said conveyer at the various elevations of said core-cutting mechanism and during the 40 operation thereof including the feed of said supplemental frame along said main frame.

65. In a mining machine, a main frame, a conveyer carried by said frame and movable longitudinally thereof, a supplementary frame mounted for longitudinal movement 45

along said main frame, an upright loop cutter carried by said supplementary frame at one side of said conveyer and having its cutting plane arranged at right angles to 50 said main frame, means for directing material severed by said cutter onto said conveyer, and means for adjusting said cutter vertically relative to said main frame.

66. In mining apparatus, a conveyer arranged to be positioned along the face of a mine vein, severing mechanism movable along said conveyer and the face of said vein to sever material from said vein and direct said material onto said conveyer, said 60 severing mechanism being movable into position in an entry at one side of the portion of said vein being worked, and a second conveyer for receiving material from said first conveyer, said second conveyer being arranged to be positioned in an entry at the side of the portion of said vein being worked opposite that in which said severing mechanism is positioned at the beginning 65 of a cut.

67. In a mining machine, the combination 70 with a supporting frame adapted to travel along a mine wall parallel thereto, of a core-cutter mounted on said frame in position to cut a core along said mine wall 75 parallel to the path of travel of said supporting frame, means for adjusting the core-cutter rectilinearly up and down relatively to said supporting frame to adjust the elevation of said core-cutter, and means 80 for propelling said supporting frame to effect rectilinear feeding movement of said core-cutter to cut a core extending away from said supporting frame.

In testimony whereof I have signed my 85 name to this specification, in the presence of two subscribing witnesses, on this 13th day of April, A. D. 1916.

EDMUND C. MORGAN.
